UNITED STATES PATENT OFFICE.

DEWEY M. KENNEDY AND BENJAMIN H. KENNEDY, OF ROCHESTER, NEW YORK, AS
SIGNORS TO KENNEDY-MCCANDLESS CORPORATION, OF ROCHESTER, NEW YORK,
A CORPORATION OF NEW YORK.

CRIB.

Application filed July 28, 1925. Serial No. 46,639.

The present invention relates to improvements in cribs, and has for its object to provide a crib having a top with improved means for facilitating its movement to and from a closing position upon the crib.

A further object of the invention is to provide means for pivotally supporting a top upon a crib for a swinging movement back and forth between a position overlying the crib and an upright position at one side thereof in such a manner as to avoid a skewing action and a consequent binding action of the top upon any part of the crib body when moving it from one position to another, regardless of the point at which the top is grasped by the operator. Another object of the invention is to provide a movable top for a crib with a simple and economical form of pivotal connection therefor, such as a bail, the ends of which are pivotally connected with the top and the intermediate portion extending the full length of the crib and pivotally connected with one of its side walls in any suitable manner. Another object of the invention is to utilize certain parts of one of the side walls of a crib to cooperate with said connection in effecting a reduction of the number of parts necessary to complete the same. To these ends the invention resides in certain improvements and combinations of parts all as will be hereinafter more fully described, the novel features being pointed out in the claims at the end of the specification.

In the drawings:

Figure 1 is a side elevation of a crib embodying the invention;

Figure 2 is an end elevation of the same with the top shown moved to a vertical position at one side of the crib;

Figure 3 is a similar view with the top shown in closing position;

Figure 4 is a detail view of a member forming a pivotal connection between the crib and the top;

Figure 5 is an enlarged fragmentary elevation taken on line 5^a—5^a of Figure 1;

Figure 6 is a detail perspective view of one of the upright side frame members showing the manner of notching or grooving the same for the reception of the pivotal connection shown in Figure 4, and

Figure 7 is a view of a modified form of connection in which the bail shown in Fig-

ure 4 is divided into separate parts, only one of which is shown.

Similar reference numerals throughout the several views indicate the same parts.

The present invention relates to cribs of the type adapted to be closed or covered for the better protection of the occupant and in providing a top for this purpose it is important that its operation or movement from one position to another to be made as simple and as easy as possible and that it be free from any binding action or tendency to skew or spring out of normal position by reason of its being operated from one end only when adjusted to its different positions.

In the present embodiment of the invention, we provide a crib body which may be of any desired type preferably constructed as indicated in the drawings and embodying the side walls 10 and 11, the end walls 12 and 13, a top or closure 13, together with the wheels 14 and a suitable bottom not shown. The side walls are preferably of the screened frame type but may be otherwise constructed as desired, or one or more of the walls may include the screening while the others may be of solid or non-screened construction. The side wall 11 preferably comprises top and bottom rails or frame members 15 and 16, together with the end and intermediate upright frame members 17 and 18 respectively, all suitably connected to form frame units for the reception of the screening 19 which may be of any approved kind, such as wire mesh or the like. The screening is secured upon the side frames and end frames as well, preferably by suitable cleats or strips 20 which are connected to the frame at the desired points by screws or nails 21 as indicated in Figure 5. The top 13 may be of any desired construction preferably including screening similar to that shown at the sides of the crib.

The pivotal connection between the top and the body of the crib preferably comprises a single member extending from one end of the crib to the other in the form of a bail, made by providing a rod 22 with right angle portions 23 and forming eyes or loops 24 thereon for the reception of the screws 25 forming means for pivotally connecting the bail with the top 13 at points intermediate its longitudinal edges as shown in Figure 3. The longitudinal portion of the bail is extended parallel with the sides of the

crib and may be pivotally connected with one of the sides by any desired form of pivotal connection, that shown in the drawing including the notched bearings or 5 grooves 27 formed in the upright frame members 17 and 18 at the inner sides of the frame as best indicated in Figure 5. These notches form bearings for the rod in which the latter is free to turn and make it unnecessary to provide separate bearings for 10 attachment to the frame as a means for supporting the rod, thus, economizing in the cost of constructing the crib. A further economy is effected by employing the screens 15 and the securing cleats therefor to maintain the rod within the grooves or notches as indicated in Figure 5, although it will be understood that the invention is not limited to this or any particular method of pivotally 20 connecting the rod with the side wall of the crib. One feature of the invention is the mounting of the longitudinally extending portion of the rod so as to have a bearing throughout its length upon the screen, or 25 other side wall surface whereby it is held in the desired position and against undue flexing during the movement of the top from one position of adjustment to another. In moving the top from the closing position 30 shown in Figure 3 to the open position shown in Figure 2 it may be grasped by the operator at either end or at any point desired and bodily pushed outwardly and at the same time swung downwardly to the position 35 shown in Figure 2, during which time the angularly disposed portions 23 of the rod swing upon the pivots 25 while the rod is swinging about the axis of its bearings in the frame. The particular advantage of 40 making a continuous pivotal support for the top and extending it along the side wall of the crib from one end to the other thereof, as distinguished from separate pivotal connections at each end of the crib, is to avoid 45 a binding action between the top and the crib body. It has been found that with the use of such separate connections, terminating at the ends of the crib that a skewing action 50 of the top occurs when operating it from one end only. In our improved construction this objection is entirely avoided because the lifting force applied at or near one end of the top is transferred by the rod through to the opposite end, thus causing even distribution 55 of the operating forces, regardless of the point at which the top may be grasped by the operator when shifting it from one position to another. This arrangement affords a decided advantage in avoiding a skewing 60 action of the top and a consequent binding action between the angular portions 23 of the rod and the crib body when adjusting the top upon the latter.

In order to securely hold the top in an upright position at the side of the crib a latch

26 is provided which is pivoted upon the side wall 11 and adapted to engage a stud 27 on the top as shown in Figure 2.

In Figure 7 we have shown a slight modification of the pivotal connection for the top, indicated at 28, wherein the rod or bail is cut at the center to form separate end portions, each of which may be independently inserted in the notches of the side frame members 17 and 18, with their ends abutting 75 or spaced slightly apart as desired, or with said ends disposed in separate notches cut in the frame member 18 if preferred. This arrangement is also adapted to prevent skewing of the top and facilitates its application 80 to the crib body by the readiness with which the separate sections of the rod may be inserted and removed when desired.

We claim as our invention:

1. In combination, a crib body, a top 85 thereof, and a member extending substantially the length of the body along one of its side walls and pivotally secured in notches formed therein and having angularly disposed ends connected with the top, said 90 member permitting the top to move bodily from a position overlying the crib outwardly and downwardly to a vertical position at the side thereof.

2. A crib body having side walls each 95 of which comprises end frame members and an intermediate frame member spaced from the end frame members, a top overlying the upper edges of said side walls, and a rod extending the full length of the body 100 below the top thereof and pivotally secured to all of said frame members, thereby affording narrow bearings for the rod at the ends of the side walls and at points intermediate said ends to hold the rod rigidly, said rod 105 being provided with angularly disposed exteriorly arranged end portions projecting exteriorly of the end walls of the crib and pivotally connected with said top at opposite ends thereof permitting it to move from a 110 position overlying the crib outwardly and downwardly to a vertical position at one side thereof.

3. A crib body having a top, one side of the crib including a frame and screening 115 thereon with cleats for securing the screening to said frame, and a rod extending substantially the length of the body and pivotally disposed upon one of its sides between said frame and said cleats and having end 120 portions connected with said top and permitting it to move from a position overlying the crib outwardly and downwardly at the side thereof.

4. A crib body having a top, one side wall 125 of the crib including a notched frame and screening thereon with cleats spanning the notch for securing the screening to the frame, and means at each end of the crib having a portion pivotally connected with 130

the top intermediate its longitudinal edges and provided with an angular portion extending longitudinally of the crib and pivotally disposed in the notches of said side 5 wall and held therein by the cleats to permit the top to move from a position overlying the crib outwardly and downwardly to a vertical position at the side thereof.

5. A crib body including side walls and 10 a cover overlying the upper edges of said side walls, one of the aforesaid elements comprising end frame members and an intermediate frame member spaced from the end frame members, a rod extending the full 15 length thereof and pivotally secured to

all of said frame members, thereby affording narrow bearings for the rod at the ends and at a point intermediate the ends to hold the rod rigidly, said rod being provided with angularly disposed exteriorly 20 arranged end portions projecting exteriorly of the end walls of the crib and pivotally connected with said other element at opposite ends thereof, permitting the cover to move from a position overlying the crib 25 outwardly and downwardly to a vertical position at one side thereof.
